COLLAPSIBLE TUBE OR THE LIKE

Gordon K. Woodard, 14155 Magnolia Blvd., Apt. 354,
Van Nuys, Calif.

Filed Mar. 30, 1964, Ser. No. 79,256

Term of patent 14 years

(Cl. D58—17)

I claim:

The ornamental design for a collapsible tube or the like, substantially as shown.
